DAVID R. LASIER, OF CHICAGO, ILLINOIS, ASSIGNOR TO NORTON-LASIER COMPANY, INC., OF CHICAGO, ILLINOIS, A CORPORATION OF ILLINOIS

DOOR HOLDER ARM

Application filed May 11, 1927. Serial No. 190,427.

My invention relates to improvements in means for stopping and holding doors, and more particularly to a type of device utilizing the relative displacement of the door and door frame when the door is opened for effecting a frictional binding by a relative movement between certain parts of a pivoted link connection between the door and door frame.

10 To this end, I have provided a stopping and holding device for doors comprising two links, the length of which may be adjustable, pivotally connected at their ends, their opposite ends being pivotally connected with 15 the door and door frame and respectively, forming three pivots in all, any one of which may be provided with cooperating frictional spiral faces adapted to engage and bind upon 20 relative movement of the parts of the particular pivot as effected by the pivotal movement of the door when being opened.

The means for effecting the frictional binding comprises a head formed at the pivot on one of any of the relatively movable parts 25 of the link connection, said head having a spiral face on one side thereof with an aperture through its middle portion, said aperture being screw threaded and adapted to receive a holding pivot bolt positioned there- 30 in. Cooperating with the friction head thus formed, is the other of the relatively movable parts which also is provided with a head having a spiral surface on one face thereof co- 35 operating with the first named spiral surface, and with an aperture mounted in pivotal relation on the bolt. The bolt is provided with a head which is capable of assuming positions of variable spacing, relative to the spiral face of the head in which it is mounted so that 40 the relative movement necessary for effecting a binding of the two heads may be varied according to the spacing provided. The bolt is provided with a lock nut on its screw threaded end whereby it is held in any desired 45 adjusted position.

One modified form of my invention contemplates the insertion of a fusible washer between the head of the bolt and the spiral face of the head in which the bolt is mounted, whereby in the event of fire, such as would

cause a fusion of the washer, sufficient space is provided between the bolt head and the spiral face for permitting an immediate release of the holding arm and a consequent closing of the door.

Inasmuch as the opening movement of the door will effect a relative movement between the parts at any of the pivots of the link mechanism connecting the door and the door frame, the frictional holding means may be placed at any of the pivots, the frictional face requiring merely for a successful operation a relative turning movement between two parts pivotally connected. The selection of a particular pivot for locating the frictional holding means will vary with different installations, it being desirable to avoid dead centers or positions of the link connection at which the translated movement of the swinging door effects only a slight relative movement between the parts of a particular pivot especially when this position occurs within a portion of the arc of swing of the door at which a stop and holding action is desired. In order to effect a more positive and efficient action, that pivot is selected which has the greatest relative movement between its parts as translated through the mechanism by the swinging movement of the door, during that portion of the arc of swing of the door at which it is desired to stop and hold the same.

It is my intention, in practicing this invention to use my improved door stopping and holding means on doors equipped with a door check closer in which case the operating levers employed for connecting the door check closer to the door or door frame, depending upon the manner of mounting the door check closer, will be replaced by levers constructed according to this invention; or, it is my intention to apply my device directly to doors which are not equipped with door check closers. It is also intended that levers equipped with my improved stopping and holding means be supplied as the operating levers with new door check closers, in which case they may both be mounted at once on new installations.

One of the objects of my invention is to provide a door stop and holding means which

is simple in construction, efficient and positive in operation, and which may be readily applied to a door of either hand, and will stop and hold a door in any selected open position.

5 Another object of my invention is to provide a door stop and holding means provided with frictional spiral faces adapted to cooperate and bind in a manner to stop and hold the door when the door has been opened to any desired extent.

Another object of my invention is to provide a door stop and holding means comprising two relatively movable parts between 15 which relative movement is effected on the opening movement of the door, said parts having frictional spiral faces cooperating in a manner to bind and hold the door at any selected open position.

20 Another object of my invention is to provide a door stop and holding means of the above described type in which the space between one of the spiral faces and the head of the bolt is variable by means of adjusting the bolt in the head by screwing it inwardly or outwardly relative to the head in which it is mounted, whereby the relatively angular movement between the links necessary for effecting a binding is varied and capable of adjustment so that the arm and stop 25 will hold the door when it has been open to any predetermined extent.

Another object of my invention is to provide a door stopping and holding means of 35 the above described type adapted for use in conjunction with door check closers or independently thereof, as connected directly between the door and door frame on doors not equipped with door check closers.

40 A further object of my invention is to provide a door stopping and holding arm of the type described in the above stated objects, in which an adjustment may be effected between the points of attachment for the 45 two arms, one of said arms being extensible and provided with pivots to permit vertical displacement of its two ends.

Another object of my invention is to provide a door holding arm of the above described type in which a fusible element is 50 incorporated and so arranged that upon fusion of said element, excess space is provided between normally wedged parts whereby, in the event of fire and fusion of said 55 element, the holding arm will be released from its wedged position and the door will be permitted to close.

These and other objects are accomplished 30 by means of the arrangement disclosed on the accompanying sheets of drawings, in which—

Figure 1 is a plane view of a door check closer and holding arm constructed in accordance with my invention installed in op-

erative position, in which case the door check and closer is carried on the door.

Figure 2 is an elevational view of the construction shown in Figure 1.

Figure 3 is a view similar to Figure 1, 70 of an installation of the opposite hand showing how the same arm may be used by merely inverting its position.

Figure 4 is a plane view similar to Figure 1 showing the door check closer attached to 75 the door frame.

Figure 5 is a view similar to Figure 4 showing the installation of the opposite hand.

Figure 6 is a detailed view in cross section of the holding arm constructed in accordance with my invention. 80

Figure 7 is a modified form of my invention in which a fusible washer is carried for releasing the device in case of fire.

Figure 8 is a view of a modified form of 85 friction device at the pivot at the end of the link which is connected to either the door or door frame, as the case may be.

Figures 9 and 10 are views showing the 90 two cooperating spiral faces constituting the frictional binding surfaces.

The various novel features of the invention will be apparent from the following description and drawings, and will be particularly pointed out in the appended claims. 95

Referring to the drawings, it will be noted that a device constructed in accordance with my invention is adapted to be connected to a door 10 and door frame 11, so that when the door is opened, turning on the hinges 12, a relative movement is effected between the pivoted parts of the connecting link work. In the type of device shown in Figures 1 and 2, a door check closer 13 is attached in any suitable manner, as by the bracket 14, to the upper portion of the door so that the operating spindle 15 will extend above the upper edge of the door in a manner to receive the operating link 16, the link fitting on the slabbed end 17 of the spindle and retained by the nut 18. Connected at the other end of link 16 is a second link designated generally as 19 pivoted by means of my improved friction stop and holding device, designated generally as 20, to be hereinafter more fully described, the other end of the link 19 being pivoted at the door frame by means of the bracket 21 secured by suitable screws 22 and attached by the bolt 23, which is fastened in the bracket 21 in the manner to form a pivot. 100

The arm 19 is made up of four separate parts to provide for adjustment as to length and flexibility in mounting as for instance, to permit the opposite end of the link work to be attached in different horizontal planes. 105 The outer end consists of a friction head portion 19a pivoted as by pin 19f to the socket member 19b, provided with a set screw 19g. The rod 19c is retained in the member 19b by the screw in any desired adjusted posi- 110

tion and has provided the universal pivot member 19d pivoted at its inner end by the pin 19e. It can be readily seen that this arrangement affords adjustability as to length, which will in turn effect the initial angularity between the parts and also permits the attaching bracket 21 to be connected at a point either elevated above or lowered out of the plane of the pivot connecting the parts 16 and 19a. Attention is further called to the fact that the two arms of my holding device are pivoted together by a pivot, the center of which lies at the intersection of the planes of the inner faces of the two arms, this type of pivot permitting the arms to be brought practically together in a manner to close the angle between them.

The portion of my device which effects the frictional holding is disclosed in Figures 6, 9 and 10 slightly enlarged, and comprises two pivoted members as shown at 19 and 16 having heads at their ends, it being understood that these may represent two relatively movable parts of any of the three possible pivots, as for instance, link 19 and bracket 21 or link 19 and link 16, or link 16 and the bracket to which it is connected in the event that a checking device is not employed; the structure of the friction holding mechanism being substantially the same irrespective of its location. The two relatively movable members are provided with heads 28 and 29, the heads 28 being formed with a spiral face on one side thereof, and with a screw threaded aperture 31 centrally disposed therethrough. Mounted in the screw threaded aperture 31 is the bolt 32 which has a smooth shank 33 at its upper portion and a head 34 on the end thereof presenting shoulders 35 spaced a predetermined amount from the spiral face 30 of the head 28. The head 29 on the arm 16 is apertured as at 36 and mounted on the bolt 32 in pivotal relationship and arranged with the washer 37 positioned between its upper face, and the shoulder 35 of the bolt. The head 29 is provided with a cooperating spiral surface 30 on its face in contact with a cooperating spiral surface 38 on the other head. From Figures 9 and 10, it will be noted that the cooperating spiral faces provide surfaces which have a step between their high and low portions, and afford relatively large surface areas between which frictional binding will occur. The parts are so disposed relative to each other, that when the arms are in the position which they are caused to assume when the door is closed, the head portions 28 and 29 are oppositely disposed, that is, the thinnest portion of the head 29 overlies the thickest portion of the head 28 and vice versa, whereby, the overall height of the two super-imposed heads is a minimum when the arms are in this position. The position of the shoulder 35 which effects the spacing providing for the movement of

the heads relative to each other, and consequent increasing of the overall height, is determined by the position of the bolt relative to the head 28 in which it is carried, and consequently, according to the adjustment when the heads move angularly relative to each other, the parts are caused to wedge and to effect a frictional binding between the contacting spiral faces of the head and the shoulder 35 of the bolt so that the parts will be locked in a new position. According to the adjustment desired, the bolt 32 is turned in its screw opening 31 and when positioned in the desired manner, the lock nut 39 is employed to maintain the particular adjustment.

In the modification disclosed in Figure 8, the friction stopping holding means 20 is positioned at the pivot connection between the link 19 and the door frame 11, the bracket 27 being similar to that shown at 21 in Figure 1, with the exception that it is modified to present a friction spiral face to form one of the elements of the friction locking means, the structure of which is shown in Figure 6.

The modification shown in Figure 7 is similar in all particulars with the device shown in Figure 6, being modified only to the extent of inserting a fusible washer 40 between the washer 37 and the head of the bolt. The fusible washer 40 provides means for effecting the initial space provided for the expanding parts under the screw action of the spiral frame, and determines together with the adjustment of the bolt, the position at which the parts will bind and lock the door in open position, but in the event of excessive heat as in the case of fire, the washer 40 will be caused to fuse and flow from its assembled position and thereby provide sufficient space between the pivotal parts to permit them to move from their frictional binding position and permit the door to be closed under the influence of the door closing element. Attention in this connection is directed to the modified form of bolt 32' which has an opening 32a centrally disposed longitudinal through the shank which serves for the purpose of conducting heat centrally of the mechanism to aid in the fusion of the washer 40.

In operation, the stopping and holding means may be applied to a door in conjunction with a door check closer as shown in Figures 1 and 2, or independently of door check closers, the inter-position of a door check closer having no effect upon the operation of my device. The door stop and holding means may also be applied to a right hand or left hand swinging door with equal success, the change from one type of door to the other merely necessitating that the device be turned over, the stopping and holding operation being accomplished when a

relatively angular position between the two members increases upon opening of the door which occurs irrespective of which side of the device is facing upwardly.

An important feature of my invention resides in the fact that I have provided a pivot for the outer ends of the arms which is symmetrical in appearance. This is found to be quite an improvement with reference to the reversibility of the holder when applied to doors of different hand. It can be seen that in installing holders on a pair of doors in a case where two doors are used for a single doorway, that is, one right and one left hand door, that it is important to have the arms symmetrical if a uniform appearing installation is desired. If a pivot is used which is not symmetrical, the reversal of one of the arms would cause one inside arm to be up and the other inside arm to be down with the result that a very ugly installation is had. With the type of holder arm which is not symmetrical and the arms of which are capable of relative movement around and around throughout 360° , the arms may be swung past each other and open up in the opposite or improper direction, so that when carpenters are installing such devices they may open the arms in the wrong manner for the purpose of obtaining a symmetrical appearance, but at the sacrifice of rendering one of the devices inoperative by movement of the cam faces in a direction opposite to that which is necessary to effect frictional binding. This is also important for the reason that it is found in practice that carpenters will not install the holders with one inside arm up and the other inside arm down because, due to the appearance they feel confident that this is wrong.

My invention eliminates any such possibility as the arms cannot be swung past each other, but are caused to swing in the same horizontal plane. This feature further provides a device which appears substantially the same regardless of the manner in which it is installed and operated and further, due to the symmetrical arrangement of the head, the arms cannot be swung past each other to open up in the improper direction and therefore cannot be improperly installed.

The selection of the particular type, that is, the locating of the friction means at a particular pivot, is dependent upon the type of door and the point along the arc of its opening movement at which it is desired to stop and hold it, the pivot selected being that which by the translated movement of the opening door effects the greatest relative movement between the pivot parts during that portion of the arc when the stopping and holding action is desired. Inasmuch as a relative movement between the two parts such as 28 and 29 in Figure 6 is effected by the opening movement of the door, it can

be readily seen that when the door is open that the member 29 will rotate on the spiral face 30 to a new position, at which time the spiral faces 30 and 31 will frictionally bind and cause a binding between the outer face of the head 29, the washer 27 and the shoulder 35 of the bolt, the spiral faces being of such gradual pitch that due to the great mechanical advantage effected by the lever parts and the door acting as a lever, relatively slight force applied at the door will cause the friction faces to hold the door in its stopped open position.

The type of stopping and holding device shown in Figures 1, 2 and 3, that is, having the friction faces at the pivot between the ends of the two links, is called the 90° type for the reason that during the opening movement of the door the movement of the parts of this pivot only cause a relative displacement of these parts of about 90° . The type disclosed in Figure 8, namely the type having the friction stop at the pivot connecting the arm 19 to the door, is called the 180° type for the reason that a 180° movement is effected at this pivot when the door is opened. It has been found in practice that the 90° type is the most satisfactory, provided it is desired to provide a means for stopping and holding the door within the first 120° of the arc of swing of the door; however, any further movement before stopping and holding necessitates that the 180° type be employed. This can be readily understood when it is known that the relative movement of the parts of the pivot of the 90° type is very slight after the door has been opened 120° , whereas, on the contrary, the relative movement between the parts comprising the 180° type is very slight until after the door has been opened 120° . It is to be noted that the holding arms whether employed with or without door closers may be mounted on either side of the door, that is, on the hinge side or on the side opposite that of the hinge side, differences in the side of mounting only necessitating different types of mounting brackets. Referring to Figures 4 and 5, it will be noted that the device represented there is mounted on the side opposite the hinge side, the bracket 25 being attached to the soffit of the door frame, and that the devices shown in Figures 1 and 2 are mounted on the hinge side. Attention is called to the fact that in either case the adjustable arm shown at 19 extends toward the doorknob side of the door and is attached remote from the hinges as compared with the attachment of arm 16.

To adjust the device it is merely necessary to loosen the lock nut 39 and adjust the bolt in its socket 31 whereby a variable space between the bolt head 35 and the spiral face 30 of the head 28 is effected. According to the particular angular displacement between the members necessary to effect the locking at the

desired opening position of the door, the nut may be caused to assume any spaced position. In a particular adjusted position the lock nut is again tightened where the parts are held.

The operation of the device shown in Figure 7 is merely one which, in case of fire, will cause a fusion of the washer 40 to permit the arms to provide more space between the shoulders, head and the cam face, whereby the arms are released and the doors are permitted to close.

I claim:

1. In combination with a door and door frame, a pair of pivotally connected arms and means for pivotally connecting said arms to the door and door frame respectively, the relatively movable parts constituting one of said pivots comprising a head having a spiral face and a step between the high and low portions thereof; a pivot bolt rigidly carried by said head, having a surface spaced from and opposed to said face, and a second head pivotally mounted on said bolt between said face and surface, also having a spiral face and a step between the high and low portions thereof, said last named face being disposed in contact with said first face, said heads being adapted to provide freedom of pivotal action throughout a predetermined range of movement and to frictionally bind throughout a relatively large contact area when the higher portions of said spiral faces come into vertical alignment.

2. In combination with a door and door frame, a pair of pivotally connected arms and means for pivotally connecting said arms to the door and door frame respectively, the relatively movable parts constituting one of said pivots comprising a head having a spiral face and a step between the high and low portions thereof; a pivot bolt rigidly carried by said head, having a surface spaced from and opposed to said face, and a second head pivotally mounted on said bolt between said face and surface, also having a spiral face and a step between the high and low portions thereof, said last named face being disposed in contact with said first face, said heads being adapted to provide freedom of pivotal action throughout a predetermined range of movement and to frictionally bind throughout a relatively large contact area when the higher portions of said spiral faces come into alignment, said bolt being capable of adjustment to alter the distance between said first named spiral face and said opposed surface.

3. In combination with a door and door frame, a pair of pivotally connected arms and means for pivotally connecting said arms to the door and door frame respectively, the relatively movable parts constituting one of said pivots comprising a head having a spiral

face and a step between the high and low portions thereof; a pivot bolt rigidly carried by said head, having a surface spaced from and opposed to said face, and a second head pivotally mounted on said bolt between said face and surface, also having a spiral face and a step between the high and low portions thereof, said last named face being disposed in contact with said first face, said heads being adapted to provide freedom of pivotal action throughout a predetermined range of movement and to frictionally bind throughout a relatively large contact area when the higher portions of said spiral faces come into alignment, and a fusible washer on said bolt occupying sufficient space between said first spiral face and said opposed surface to permit release of the binding action upon fusion thereof.

Signed at Chicago, Illinois, this 5th day of May, 1927.

DAVID R. LASIER.
